Primary Examiner — Cathron C Brooks(74) *Attorney, Agent, or Firm* — Myers Wolin, LLC(57) **CLAIM**

The ornamental design for a crib tent, as shown and described.

DESCRIPTION

FIG. 1 is a front top right perspective view of one embodiment of a crib tent showing my new design;

FIG. 2 is a back bottom left perspective view thereof;

FIG. 3 is a front view thereof;

FIG. 4 is a rear view thereof;

FIG. 5 is a right side view thereof, the left side view being symmetric therewith;

FIG. 6 is a top view thereof;

FIG. 7 is a bottom view thereof; and,

FIG. 8 is a front top perspective view thereof shown in the context of a crib with a mattress.

The dashed lines illustrate environmental structure and form no part of the claimed design. The random cross hatching marks on the lower part of the crib tent represent fabric, not surface ornamentation. The cross hatching in the rest of the crib tent illustrates netting.
